ARCHERY BOW AND METHOD OF FABRICATION
Sylvester Louis Chessman, Ellsworth, Mich., assignor to
Morweil Steel Products Corporation, Ellsworth, Mich.,
a corporation of Michigan

Filed Sept. 8, 1961, Ser. No. 136,871
2 Claims. (Cl. 124—24)

This invention relates to a precision-type take-apart archery bow and more particularly to a take-apart archery bow provided with limbs having cast-in-place resin encapsulated butt ends that are flexibly mounted on a unitary recessed central handle limb retainer member and the method for fabricating a take-apart archery bow with an automatic zeroed-in feature.

While take-apart bows are well known in the prior art, none of these bows have provided a take-apart bow wherein the precision and quality usually found only in unitary archery bow instruments has been preserved. Generally, the take-apart devices of the prior art have consisted of solid central handle sections whose ends have been co-axially drilled or bored to provide limb-receiving holes into which the limbs are inserted. These central handle sections have either been of solid unitary construction or have consisted of mating sections between which the limbs are mounted. In still other devices of the prior known art, extraneous detachable clamps have been provided on the handle portion so as to receive the limb members.

In such devices of the prior art, the limb members have been attached and fitted to the socket portions of the handle member by use of wedge members, pins, set screws, external clamps, hinges and the like, that act directly upon the limbs in order to connect them directly to the handle member.

The effect of this type of multi-piece segmental construction has been to provide a bow which did not have the precision and high quality performance of one-piece bows. The use of these various wedge and pin members has generally resulted in loss of energy because there was no smooth interaction between the parts, thereby providing a bow which was relatively inefficient. In addition, the use of these various elements in fabricating a multi-piece bow has resulted in loss of accuracy in the operation of the final product due to the absence of overall alignment between the co-acting segments.

In the fabrication of the devices of the prior art, no thought has been given to the provision of a multi-piece archery bow having precision-type construction whereby a rigid handle element is provided having "matched" limbs, thus eliminating the need for the use of wedges or other shim means to complete the bow. The central handle portions of the devices of the prior art have either consisted of solid members provided on each end with hole sockets to receive limb members or have consisted of elaborate and complex hinge structures to which limb members were attached. Nowhere in the prior art has the concept been utilized of a rigid U-frame or open channel central handle portion provided with longitudinally disposed recesses at the ends thereof into which the butt ends of "matched" limbs are positioned in a nest relationship to provide a multi-piece bow having the performance characteristics of a one-piece integrally formed archery bow unit.

In the instant invention, the use of "matched" limbs having cast-in-place resin encapsulated butt ends along with the rigid U-frame handle portion provides an archery bow having a "solid" feeling. This is due to the fact that the butt end of the finished limb bears on all surfaces of the limb receiving recesses or sockets provided in the handle member.

In addition, the limb retaining socket is completed by

2

use of a flexible retainer cap plate or lock element to form a flexible wall of the limb retaining socket or recess against which the butt end of the limb bears when the bow is drawn. The retainer cap plate or lock element is drawn against the exposed side surface of the butt end of the limb thereby retaining the butt end within the limb receiving recess portion of the rigid handle member. Inasmuch as the retainer cap plates are positioned on the "inside" or archer's side of the handle unit, they flex with the limbs when the bow is drawn thereby providing greater stability and a more controlled release of energy during the drawing and release of the bow.

Nowhere in the prior art is there found a take-apart bow having a socket portion whereby the archer's or "inside" wall of the socket flexes or gives when the bow is drawn. The flexing of the cap plates also enhances the storage and release of energy because the bending of the limbs is thus distributed over a larger area as opposed to the bending which occurs across the outer edge of a rigid socket which consists merely of a coaxially bored hole provided in a handle portion and which does not employ the flexing concept found in the instant invention.

None of the devices of the prior known art utilize the concept of limbs having cast-in-place resin encapsulated butt ends whereby the walls of the socket portion matingly bear against the sides of the butt ends with 100 percent area contact, thus providing for a more effective storage and release of energy and a more "solid" feel to the bow. In addition, as will be described hereinafter, the use of this method provides limbs that are automatically "zeroed in" for any particular handle.

A problem that has always existed in the archery bow field has been that the limbs of a bow, particularly a take-apart bow, did not always bend in a single plane (the plane established by the center line of the handle portion) during the drawing and release of the bow. This has generally resulted in sub-par performance and has brought about the need for time-consuming and costly corrective maintenance. A need has therefore existed for a bow and method for fabricating a bow that would automatically insure flexure of the limbs in the plane of the handle center line thereby avoiding loss of energy and resulting in greater accuracy.

The use of this method also makes it possible for a single handle member to be provided with several sets of mating limbs whereby each set is designed for a specific purpose, such as hunting, target shooting and the like.

Further, none of the devices of the prior known art teach the use of a channel type construction in the central handle portion of a take-apart bow so as to provide a rigid structure having high strength characteristics while being light in weight due to its hollow recess construction. The rigidity of this type of central handle also helps to eliminate the loss of energy when the bow is drawn and subsequently released inasmuch as the flexure of the bow occurs primarily in the limb members. The U-frame design also provides a hollow bow having versatility in use because the bow may be easily balanced by simply utilizing a weighted filler material in the handle portion as required.

In addition, none of the take-apart bow devices of the prior known art utilize a detachable grip portion which matingly engages the handle portion of the bow. The detachable grip portion can be fitted for the grip of the individual archer. Thus, the take-apart bow of the instant invention can be mass produced while maintaining custom-built characteristics due to the use of an individualized grip member which matingly engages the standard handle portion.

It is therefore an object of this invention to provide

a take-apart bow having limbs with cast-in-place resin encapsulated butt ends.

A further object of this invention is to provide a take-apart bow having a rigid central handle member of a unitary open channel construction.

A still further object of this invention is to provide a take-apart bow whereby flexible retainer cap plates are utilized to retain the butt ends of limbs within the socket or recess portions of the handle member.

Another object of this invention is to provide a take-apart bow wherein one wall of the limb retainer socket portions consist of a retainer cap plate which yieldably bears against the butt end of the limb thus retained.

Another object of this invention is to provide a unique method whereby a limb having a cast-in-place butt end is provided by the use of a plastic resin filler to form an encapsulating layer around the butt end of the limb.

Still another object of this invention is to provide a take-apart bow having a U-frame channel type handle portion and "matched" limbs that are automatically "zeroed in" so as to bend only in one plane.

Yet another object of this invention is to provide a take-apart bow having a "solid" feel because the walls of the butt ends of the limbs have 100 percent area contact against the walls of the socket portions of the bow.

Another object of this invention is to provide a take-apart bow that may be easily counterweighted due to its hollow U-frame channel construction.

Still another object of this invention is to provide a take-apart bow wherein storage and carrying space is easily provided by virtue of its hollow U-frame configuration.

Another object of this invention is to provide a take-apart bow having a detachable grip member which may be custom designed for the grip of the individual archer using the bow.

A still further object of this invention is to provide a take-apart bow having a handle portion which is lightweight but which is not likely to warp when exposed to heat or inclement weather.

Yet another object of the invention is to provide a take-apart bow having great versatility in use due to its design and method of construction whereby interchangeability and replacement of parts is enhanced while maintaining high quality and high performance.

Other objects and advantages found in the construction of my invention will be apparent from a consideration of the following specification in connection with the appended claims and the accompanying drawings.

In the drawings:

FIGURE 1 is a side elevation view of the assembled take-apart bow illustrating the limbs having cast-in-place resin encapsulated butt ends mounted on the central U-frame handle member and showing the detachable grip mounted thereon.

FIGURE 2 is a front elevation view of the central portion of the assembled take-apart bow illustrating the configuration of the central U-frame channel type handle member and the detachable grip as shown in FIGURE 1.

FIGURE 3 is a rear elevation view of the U-frame handle member of the take-apart bow, as viewed from the "rear" or archer's side, illustrating the overall unitary channel type configuration thereof with limb retaining recesses or sockets provided therein and showing the butt end of a limb in place within one of the recesses or sockets.

FIGURE 4 is a cross-sectional view of the handle member taken on line IV-IV of FIGURE 3 so as to illustrate the U-frame cross-sectional channel configuration of the handle member.

FIGURE 5 is a partial exploded view of the take-apart bow illustrating the upper limb retaining recess or socket end of the handle member, the resin encapsulated butt end of the limb which matingly and nestingly engages

the recess or socket end of the handle member, the upper retaining cap plate and the retaining screws.

FIGURE 6 is a perspective view of the flanged lower retaining cap plate which matingly fits into the lower socket portion of the handle member so as to bear against and retain the butt end of a limb mounted therein in nest position.

FIGURE 7 is a cross-sectional view of the upper socket portion of the assembled take-apart bow taken on line VII-VII of FIGURE 1 illustrating the complete nestng contact between the encapsulated butt end of the limb and the socket portion and, further, showing the retaining cap plate bearing solely upon the butt end of the limb as the retaining screws draw the retaining cap plate thereagainst.

FIGURE 8 is a perspective view of the detachable grip portion which matingly engages the U-frame handle member of the take-apart bow.

FIGURE 9 is a perspective view of the spacer cover member which is mounted on the U-frame handle member directly above and below the rear of the detachable grip member.

FIGURE 10 is a schematic front elevation view of the U-frame handle member mounted on parallel rest bars on a gauge reference table with rough butt ends of limbs mounted therein by use of C-clamps so that the limbs may be suitably shimmed to bend solely within the horizontal plane established by the center line of the U-frame member.

FIGURE 11 is a schematic top view of the U-frame handle member, as shown in FIGURE 10, and showing in phantom line the method of flexing the limbs so as to determine the amount of shimming necessary to insure flexure of the limbs solely within the horizontal plane of the center line of the handle member.

FIGURE 12 is a cross-sectional schematic view of the socket portion of the handle member containing the shimmed butt end of the limb held in place by a C-clamp and illustrating the encapsulating resin filler poured into the socket around the shimmed butt end of the limb (including the shim members) so as to build the butt end of the limb up to the exact size of the socket portion and thus provide a limb which is automatically "zeroed in."

FIGURE 13 is a side view of a limb used in the take-apart bow and illustrating the reinforcing wedge utilized to build up the butt end of the limb.

FIGURE 14 is a front view of the limb showing the narrow configuration of the butt end of the limb made possible by the use of the wedge member and illustrating in phantom-line the width of the limb which would have been necessary without the use of the wedge member.

General Description

In general, a take-apart archery bow is provided having two "matched" limbs with cast-in-place resin encapsulated butt ends and a rigid central handle member. The central handle member consists of an elongate channel member of U-shaped cross section and having precision machined limb retaining recesses or socket portions at the ends thereof. The butt ends of the limbs are nestingly positioned within the longitudinally disposed socket or recess portions of the handle member and on three sides have 100% percent area contact therewith.

As will be described hereinafter, the rough butt ends of the limbs are "zeroed in" during fabrication thereof by shimming them within the socket portions of the handle so that they bend only in the plane established by the longitudinal center line of the handle. After they have been properly shimmed, an epoxy resin is poured into the socket portions of the handle around the rough butt ends of the limbs so that the butt ends and shims are encapsulated in situ. Thus, once the epoxy resin hardens, removable limbs are provided having butt ends that are

perfectly mated with the precision surfaces of the socket portions of the central handle member.

Inasmuch as the U-channel handle member obviously does not provide an enclosed socket portion for the retention of the limbs therein while the bow is in use, a retainer cap plate is provided across the longitudinal open portion of the limb receiving recess which faces the rear or archer's side of the bow. In this position, the retainer cap plate bears against the rear side of the butt end of the limb, thus retaining the butt end of the limb within the socket portion of the handle member. Retainer screws are provided which engage the front wall of the U-channel handle member, pass freely through holes provided in the butt end of the limb, and engage the oppositely positioned retainer cap plate so as to draw it into retentive engagement against the rear or exposed side of the butt end of the limb.

In use, the handle member is oriented so that the open portion of the handle faces to the rear or archer's side of the bow. In this manner, the butt end portions of the limbs bear directly against the retainer cap plates while the bow is drawn. The retainer cap plates thus tend to give or flex when the bow is drawn and therefore provide for a smoother storage and release of energy in use. In the preferred embodiment of the invention, the retainer cap plates are tapered so as to enhance this flexing action. In addition, it should be noted that the retainer cap plates bear solely against the resin encapsulated butt end of each limb and do not engage the edges of the handle member.

The U-channel construction of the handle member not only provides an inherently stable rigid handle element that does not bend in use, but in addition provides a hollow structure which not only receives the encapsulated butt ends of the limbs but which may easily be counterweighted at any desired point. In addition, carrying or storage compartments may be provided in the handle as desired or the handle may be filled with an epoxy resin filler to provide any overall desired weight and additional strength to the bow.

A detachable grip member having a customized outer surface is provided which slides over the outside of the U-frame handle portion and is detachably secured thereto. In this manner, the grip portion of the handle may be easily changed to provide individuality to the bow in accordance with the particular grip requirements of the archer.

Further, as will be hereinafter described, a unique method is provided for fabricating limbs with resin encapsulated butt ends that are cast-in-place within the actual sockets or recesses in which they are ultimately used.

It is thus seen that a highly versatile bow is presented having take-apart and interchangeability characteristics while maintaining precision performance and accuracy.

Specific Description

More specifically, the take-apart bow, as shown in FIGURE 1, consists of a central handle member 20, limb members 21, an upper retaining cap plate 22, a lower retaining cap plate 23, and a detachable grip member 24. As shown in FIGURE 3, the central handle member 20 is an elongate unitary structure of channel type construction having a U-shaped cross-sectional configuration, as shown in FIGURE 4. The handle member 20 is configured to provide a longitudinally disposed upper limb retaining recess or socket 25 and a longitudinally disposed lower limb retaining recess or socket 26 at the ends thereof. The center portion 27 of the handle 20 is offset in the manner well known in the archery art and, as shown in FIGURE 3, may be filled with a resin filler 28 to provide added stability. The central handle member 20 may be stamped or forged out of any suitable material, such as aluminum or steel. The preferred embodiment consists of anodized aluminum. It is also within the scope of this invention to fabricate the U-frame handle member 20 from plastic

resins having the characteristics necessary to provide the rigid structure described herein.

The inner surfaces of the socket or recess portions 25 and 26, are machined to achieve precision surfaces. In the preferred embodiment, these surfaces are perpendicular to each other and are flat. However, other configurations may be used, such as semi-circular or modified V-shape cross sectional designs. The central or front wall of each socket or recess portion 25 and 26 is provided with retainer screw holes 29. The retainer screw holes 29 are countersunk on the front face of the handle member 20. The heads of the retainer screws 30 engage the countersunk portion of the screw holes 29, but the stems of the screws 30 extend through the holes 29 into the limb receiving recesses or sockets, 25 and 26.

The limbs 21 consist of wood and fiberglass laminates and are fabricated in a conventional manner well known in the art, with the exception of the use of a wedge member 33 to build up the butt end of the limb. As shown 20 more specifically in FIGURES 13 and 14, the limbs 21 are unique in that a reinforcing wedge member 33 is utilized to form the butt end 32 of the limb 21. The wedge is fabricated from wood, but plastic or wood-plastic laminate construction can be used. The added thickness made 25 possible by use of the wedge member 33 enables the butt end 32 to have the narrow width necessary to matingly engage the socket or recess portions of the handle. Without the added thickness, the limbs would split in use if a narrow width were maintained in the butt end. As shown 30 in the phantom line of FIGURE 14, the butt end of the limb would have to be wider in order to avoid such splitting.

Limb retaining screw holes 31 are provided through the butt ends 32 of the limbs 21. The limb retaining screw 35 holes 31 are of a sufficiently large diameter to allow the retainer screws 30 to pass freely therethrough so as to engage the threaded holes provided in the retainer cap plates 22 and 23.

As will be hereinafter described, the butt end 32 of each limb 21 has been coated or encapsulated with a resin material so as to provide "zeroed in" 100 percent area contact between the wall surfaces of the butt end 32 of each limb 21 and the walls of the limb retaining recesses or sockets 25 and 26. The exploded view of FIGURE 5 and the cross sectional view of FIGURE 7 illustrate the interrelationship between the limb receiving recess or socket portion of the handle 20, the resin-encapsulated butt end 32 of the limb 21, the retainer cap 22 and the retainer screws 30. For purposes of clarity, the thickness of the encapsulating resin layer 34 is slightly exaggerated in the cross-sectional view of FIGURE 5. In the preferred embodiment of the invention, an epoxy resin is utilized to encapsulate the butt end of the limb, but any other type of plastic material having similar qualities may be utilized.

The retainer cap plates 22 and 23 are configured to extend slightly into their respective socket or recess portions, 25 and 26, so as to bear against and thus retain the butt end of the limb in a nest relationship within the recesses or sockets. The retainer cap plates 22 and 23 are provided with flange extensions 35 which extend over but do not engage the edges of the handle member 20. This relationship is clearly shown in FIGURE 7 wherein the retainer cap plate 22 bears solely upon the butt end 32 and its encapsulating layer 34. A tapered upper surface 36 gradually reduces the thickness of the end portion of each retainer cap plate so as to permit a limited controlled flexure of the cap plates 22 and 23 when the bow is drawn and the limbs 21 increase their pressure against the retainer cap plates. This brings about greater stability when the bow is drawn and subsequently released. The unique positioning of the retainer cap plates across the rear of the socket or recess portions in effect provides a socket member which has a flexible rear wall against which the butt end of the limb bears when it is being drawn. The 70 retainer screws cooperate with the retainer cap plates to

provide resilient lock means which yieldably secure the limbs within the limb retainer handle.

A detachable pistol-type grip element 24 is provided which slides into frictional mating and enveloping engagement with the central portion 27 of the handle element 20, as shown in FIGURES 1 and 2. The detachable grip 24, shown in the prospective view of FIGURE 8, is configured so as to matingly engage and cover the central outer portion 27 of the handle member 20 and is provided with an outer surface which may be shaped to fit the grip of any individual archer. The inner surfaces of the grip member matingly conform to the outer configuration of the central portion 27 of the handle member 20 so that it may be easily slid into position thereon. The grip 24 may be cast or fabricated from any suitable material, either a wood laminate or a lightweight plastic. The grip 24 is attached to the handle member by use of suitable screws.

An elongate contoured grip spacer member 38 is affixed to the front face of the handle member, as shown in FIGURES 1 and 2. The contoured grip spacer member 38 cooperates with the grip member 24 so as to complete the detachable grip portion around the central portion of the take-apart bow.

It is within the scope of the invention to alter the configuration of the detachable grip member as desired. Experience may show that it would be more economical to fabricate the grip in two substantially similar half portions. The important feature is to provide a readily detachable grip element which may be designed to fit the hand of any given archer and which is easily mountable upon the standard handle portion.

Spacer cover members 39, shown in FIGURE 9, are provided to engage and extend into the handle member 20 as shown in FIGURES 1 and 2. These cover members 39 are positioned between the retainer cap plates and the detachable grip 24 and serve to cover the open portions of the handle member 20 and are secured thereto by use of screws which engage the side walls of the handle and pass through a hole provided in the extension of the spacer member. Thus, the spacer cover members provide a stabilizing as well as decorative effect in that the walls of the handle are anchored thereagainst.

It is thus seen that a highly versatile take-apart bow is provided. The use of the channeled or recessed construction provides a handle portion which is rigid yet lightweight. Any unused portion of the hollow handle may be filled by plastic or other filler material to balance the bow as desired and to give the bow any desired total overall weight. These hollow portions of the bow may be provided with suitable covers so as to provide storage space for auxiliary archery and hunting equipment, such as a compass, extra strings, glue, matches, arrow knobs and the like. An arrow rest shelf or shoulder 37 is provided integral with the detachable grip portion 24 and the bow is strung by use of string 46. Sight devices may be easily attached to the handle as desired.

Operation

In the preferred embodiment, the limb retainer handle member 20 is fabricated by stamping so as to provide recess or socket portions 25 and 26. However, the handle member 20 may be forged, cast or molded, depending on the material being utilized. The inner walls of the recess or socket portions are then precision machined to provide accurate limb contact surfaces.

As shown in FIGURES 10 and 11, the handle member 20 is then horizontally positioned on a reference surface (gauge table) 40 by use of parallel rest blocks 41 so that the center line 42 of the handle member 20 is parallel to the horizontal reference surface of the gauge table 40. After the recesses or sockets have been coated with suitable resin release agents, the rough butt end 32 of a limb 21 is then clamped into its use position in each recess or socket portions 25 and 26 by use of C-clamps 43. Care

is taken that the horizontal axis of the limb falls in the same horizontal plane as the center line 42 of the handle member 20.

While the handle member 20 is held in a fixed horizontal position on the blocks 41, each limb 21 is flexed through an arc from its free position to its full drawn position. This flexing action is shown in phantom line in FIGURE 11. A height gauge 44 is utilized to determine whether or not the tip of the limb remains in the horizontal plane of the handle center line 42 throughout the entire course of the flexure of the limb 21. If, during the test flexing, the tip of the limb varies from the horizontal plane established by the center line 42, the butt end of the limb 21 is shimmed to insure that the limb 21 will bend only in the plane of the center line 42. This corrective shimming automatically provides a limb which is "zeroed in" on the handle. After the limbs 21 have been thus aligned in their use position on the handle 20, the recesses or sockets 25 and 26 are filled with an epoxy resin which flows around the butt end 32 of the limb 21 so as to form the encapsulating layer 34. As shown schematically in FIGURE 12, the encapsulating resin layer 34 solidifies around the shim members 45, thus making them an integral part of the butt end 32. Due to the effect of the aforementioned release agent, each limb is then easily removed from its respective socket.

Thus, the butt end 32 of each limb 21 is aligned and cast-in-place in its respective socket thereby providing a limb 21 which is automatically "zeroed in" on the handle member 20. Further, the cast-in-place method of fabrication insures that the butt end of the limb fits its socket or recess with 100 percent area contact thereby imparting a "solid" feel to this invention which is not usually found in the take-apart devices found in the prior art. The retainer cap plate engaging surface of the encapsulated butt end 32 is then milled down to provide an even surface for the retainer cap plates, 22 or 23, to bear against in the manner shown in FIGURE 7. The thickness of the finished butt end is such that the retainer cap plate engages the butt end but does not bear against the handle member. Thus, in its assembled use position, the retainer cap plate bears against the butt end of the limb and flexes with the limb when the bow is drawn.

The take-apart bow is assembled by mounting the butt ends of the "matched" limbs into their respective recesses. The retainer cap plates are drawn thereagainst by use of the retainer screws in the manner previously described. The assembly of the take-apart bow is completed by mounting of the detachable grip thereon. After the spacer members 39 and contour strip 38 have been attached, the bow is ready for stringing and subsequent use.

A take-apart bow is provided having great versatility in use due to the interchangeability of the various components of the bow. For instance, several sets of "matched" limbs may be provided for use on a single handle. Thus, an archer could utilize the same handle but change the limbs as required for hunting, target shooting and the like.

The use of the flexible retainer cap plates, the cast-in-place "matched" limbs, and the detachable grip member provides a take-apart bow which has performance characteristics usually found only in one-piece custom built bows.

Various other modifications of the invention may be made without departing from the principle thereof. Each of the modifications is to be considered as included in the hereinafter appended claims unless these claims by their language expressly provide otherwise.

Having thus set forth the nature of the invention, I claim the following:

1. In a take-apart bow, the combination comprising a limb retainer handle member defining a pair of oppositely positioned limb receiving rearwardly open channel openings, said openings so defined, being elongate in said retainer handle; limbs having cast-in-place resin encapsu-

lated butt ends which are selectively insertable and removable from said openings and nestable therein; and elongate retainer cap plate elements flexibly provided in said openings, said retainer cap plate elements bearing against the exposed surface of said resin encapsulated butt ends in said nest position; and means provided through said butt ends to lockably engage said retainer cap plate elements to said handle member, said retainer cap plate elements flexibly bearing solely against said resin encapsulated butt ends.

2. In a take-apart bow wherein a limb retainer central handle member utilizes flexible retainer cap elements to lockably and flexibly retain the butt ends of limbs in elongate limb receiving rearwardly open channel openings provided therein, the combination comprising: limb members consisting of molded laminated layer elements and being configured for use in a take-apart bow having a central handle member; and a resin encapsulated butt end

portion provided on each of said limb members, said butt end portion formed by use of a substantially wedge-shaped filler member intermediate said laminate layer elements.
